UNITED STATES PATENT OFFICE.

ALBERT W. HAM, OF LANSINGBURG, NEW YORK.

TROLLEY-TENDER.

SPECIFICATION forming part of Letters Patent No. 691,264, dated January 14, 1902.

Application filed June 13, 1901. Serial No. 64,419. (No model.)

To all whom it may concern:

Be it known that I, ALBERT W. HAM, a citizen of the United States, residing in Lansingburg, in the county of Rensselaer and State of New York, have invented a new and useful Improvement in Trolley-Tenders, of which the following is a specification.

My invention relates to trolley-tenders for reeling in the slack of trolley-cords attached to the trolley-carrying poles of ordinary construction which are used on cars in overhead-wire electric traction systems.

The functions to be performed by the trolley-tender are as follows: to reel in slack off the trolley-cord as the trolley is depressed, as when the car goes under a bridge, and to pay out the trolley-cord as the trolley rises, as when the car comes from under a bridge, and also, in case the trolley jumps from the wire, to catch the cord immediately and prevent the trolley-pole from swinging violently to a vertical position. The dangers and inconveniences which result from this accident are too well known to require description.

In the drawings hereto annexed I have shown one form in which my invention may be embodied.

Figure 1 is a front view of my improved trolley-tender; Fig. 2, a vertical transverse section, and Fig. 3 a sectional elevation on the line 3 3 of Fig. 2 looking from the back side.

The trolley-tender is secured to a convenient place on the car, preferably to the rear dashboard, just above the usual place for the dashboard-lantern. The mode of attachment shown in Fig. 1 is by a blade G, which is secured to the dashboard at g' and offset slightly at g², so that by means of a slot in the rear part of the tender-case, presently to be described, the trolley-tender may readily be slipped on and off the blade g. A notch g³ in the free end of the blade G serves to retain the hook g⁴, which is attached to the tender-case by a chain g⁵. This hook keeps the trolley-tender in place on the blade G.

The trolley-cord T, or a flexible chain or band which may be attached to the trolley-cord, enters the tender-case at the opening e², Fig. 1, and winds around the spring-actuated reel C', which is mounted inside the case.

The form in which I prefer to construct my

improved trolley-tender is shown in Fig. 2. A back plate B is formed with an annular flange B', which surrounds the shallow cylindrical chamber B², and secured to or integral with the disk B, at the center thereof, is the spindle A, which projects toward the front of the trolley-tender. The disk B is provided with the shallow transverse groove a at the back, which provides for the insertion of the supporting-blade G. The outer casing of the trolley-tender is in two parts—namely, a front plate E and a back plate F—which are provided with flanges which fit one over the other, the flange in the back plate F fitting around the periphery of the disk B. The back plate F is cut away opposite the groove a, so that the tender may be slipped on or off the blade G, Fig. 1. Screws e secure both the plates of the casing to the peripheral portion of the disk B. The pipe e², situated in the front plate E, provides an opening for the passage of the trolley-cord T. The cord T is wound upon the reel C', which in the form here shown is secured to or integral with the disk C. A circular plate C², secured, as at c, to the reel C', completes the trolley-cord-holding portion of the device. The disk C and reel C' are mounted to rotate upon the spindle A, and the front plate E is secured to this spindle by a screw and washer, as at a'. Under normal conditions the tension of the trolley-cord T is maintained by the spring S, which is coiled around the spindle A and secured thereto at c' and to the inside of the reel C' at c², in such manner that the spring S resists the unwinding of the cord T and winds in the slacks as the trolley-pole descends. So long as the trolley is properly in contact with the overhead wire its rise and fall are responded to by the unwinding and rewinding of the cord upon the reel C'; but if for any reason the trolley jumps from the wire the reel C' is instantly arrested and the ascent of the trolley-pole prevented. This is accomplished by the following contrivances.

In Fig. 3 my trolley-tender is shown in section along the line 3 3 in Fig. 2, viewed from the back side of the trolley-tender, as indicated by the arrow in Fig. 2. The flange B' deviates internally from the true cylindrical form, the space B³ constituting an eccentric enlargement in the chamber B², the said en-

largegement B^3 terminating at the shoulder B^4 . In the periphery of the disk C , I provide a suitable number of pockets d , in each of which there is placed a roller D , these rollers lying loosely in their respective pockets. As the trolley-cord winds and unwinds under normal conditions the rollers D remain in the pockets d , their weight being sufficient to overcome the slight centrifugal tendency during the period when in the rotation of the disk C the rollers D are passing by the enlargement B^3 of the chamber B^2 ; but if the trolley leaves the wire and the trolley-pole starts to spring toward the vertical position the increased speed with which the disk C rotates causes that one of the rollers D which first passes across the enlargement B^3 of the chamber B^2 to leave its seat in the pocket d and to assume the position shown by dotted lines in Fig. 3 at D' . In this position the roller is carried around to the shoulder B^4 , where it is arrested, and the shoulder C^4 of the pocket d brings up against the roller, as shown in dotted lines in Fig. 3. The radial depth of the chamber enlargement B^3 , measured from the periphery of the disk C , is less than the diameter of the rollers D , so that the displacement of a roller from its pocket is sure to arrest the rotation of the disk C , as described, and so that the rollers cannot be caught between the periphery of the disk C and the wall of the enlargement B^3 .

This device for arresting the unwinding of the trolley-cord in case of accident is extremely simple and surprisingly sensitive. Its sensitiveness may be increased or diminished by shifting the location of the shoulder B^4 with relation to the horizontal diameter of the disk C or by altering the inclination of

the sides of the pockets d with relation to the 40 radii of the disk C . The arrangement here shown, where the enlargement B^3 is located in an upper quadrant of the chamber B^2 , with the shoulder B^4 near the horizontal diameter of the chamber, is recommended as efficient. 45

What I claim, and desire to secure by Letters Patent, is—

1. In a trolley-tender, the combination of a spring-controlled reel, catch-pockets secured thereto, roller-catches in the pockets, and a 50 shoulder whereby a roller-catch is arrested when the catch is centrifugally moved from its seat in the pocket.

2. In a trolley-tender, the combination of a spring-controlled reel, catch-pockets secured thereto, a cylindrical chamber wherein the 55 pockets rotate, provided with an enlargement, roller-catches in the pockets, the said enlargement terminating in a shoulder whereby a roller-catch is arrested when the catch is centrifugally moved from its seat in the pocket. 60

3. In a trolley-tender, the combination of a spring-controlled reel, catch-pockets secured thereto, a cylindrical chamber wherein the 65 pockets rotate, provided with an enlargement in one of its upper quadrants, roller-catches in the said pockets, the said enlargement terminating in a shoulder at or near the horizontal diameter of the cylindrical chamber, whereby a roller-catch is arrested when the 70 catch is centrifugally moved from its seat in the pocket.

Signed by me at Troy, New York, this 10th day of June, 1901.

ALBERT W. HAM.
